UNITED STATES PATENT OFFICE.

EDWARD FAVREAU, OF WORCESTER, MASSACHUSETTS.

BLIND-FASTENER.

SPECIFICATION forming part of Letters Patent No. 736,949, dated August 25, 1903.

Application filed July 30, 1902. Serial No. 117,618. (No model.)

To all whom it may concern:

Be it known that I, EDWARD FAVREAU, a citizen of the United States, residing at Worcester, in the county of Worcester and State of Massachusetts, have invented a new and useful Blind-Fastener, of which the following is a specification.

This invention relates to an attachment for fastening window-blinds in their shut or closed position.

The especial object of this invention is to provide a strong, simple, and inexpensive construction for locking window-blinds, which attachment may be readily and quickly applied to blinds now in use without interfering with the ordinary blind catches or fixtures employed thereon.

To these ends this invention consists of the fastening attachment for blinds and of the combinations of parts therewith, as herein-after described, and more particularly pointed out in the claim at the end of this specification.

In the accompanying drawings, Figure 1 is a fragmentary view of sufficient parts of a window casing and blind to illustrate the application of my invention thereto. Fig. 2 is an enlarged transverse sectional view of the same. Fig. 3 is a detail view illustrating the fastening-clip which may be employed on one of the blinds, so that a single fixture may be employed for holding both blinds closed; and Fig. 4 is a detail sectional view, partially broken away, of a blind-fastener constructed according to this invention.

The ordinary window-catches which are now employed for locking windows at night or at other times when it is desired to prevent an entrance being made through a window usually require the window to be closed. In many cases, especially in warm weather, it is desirable to leave the window open and at the same time to prevent an entrance from being made through the window. To accomplish this purpose, I have provided a locking attachment which may be applied to the ordinary window-blinds and which will serve to lock the window-blinds from the inside, so that the windows may be raised, but an entrance through the same may be prevented by locking the blinds in their shut or closed position.

My attachment has been especially designed to provide a strong, simple, and inexpensive construction which may be applied without interfering with any of the ordinary blind snaps or fixtures now ordinarily employed.

A blind attachment constructed according to my invention consists, essentially, of two parts or pieces—that is to say, it comprises a hasp or hook, which is fastened to one of the blinds, and a socket-piece, which is secured to the window-sill. When the blinds are closed, the hasp or hook may be dropped into the socket-piece and may be fastened therein by a locking-screw. A small key or wrench is preferably employed for turning the locking-screw, so that the fixture cannot be unlocked after having once been fastened except by the party having possession of the key. A single attachment of this construction may be employed for holding both blinds shut by providing one of the blinds with a clip or locking piece which engages behind the blind which is locked or fastened by the attachment.

Referring to the accompanying drawings for a detail description of a blind-fastener constructed according to my invention as shown in Fig. 1, A designates a portion of an ordinary window-casing. Pivoted to the window-casing A in the ordinary manner is a blind B, which may be swung in over the window-sill C. Shutting onto the window-sill is the window-sash D. These parts may be of the ordinary construction and need not be herein described at length.

The blind-fastener, as herein illustrated, comprises a hasp carried by one of the blinds. The hasp may consist of a pivot-piece 10, having a base-section with screw-holes therein for receiving the screws which fasten the same to the blinds, while pivoted in the piece 10 is a hook or hasp 11. Secured on the window-sill C in position to coöperate with the pivoted hook or hasp 11 is a socket-piece 12. The socket-piece 12 is provided with a base-plate 13, which is perforated to receive the screws which hold the same in place. Threaded transversely into one side of the socket-piece 12 is a locking-screw 14. As shown most clearly in Fig. 4, the locking-screw 14 is pointed or rounded at its inner end to engage a depression or socket near the end of

the hook or hasp 11. At its outer end the fastening-screw 14 is provided with a squared section 15, which may be engaged and turned by a wrench or key 16. By means of this construction the locking attachment will not interfere with the opening or closing of the window-blinds except when the hasp is turned up and dropped into the socket-piece 12. When this has been done and the tightening-screw turned by the key 16, the blind cannot thereafter open or swing back unless it has been first released by the person having the key.

A single attachment of this kind may be employed for locking a pair of window-blinds by providing one of the blinds, as E, (illustrated in Fig. 3,) with a clip or tongue piece 17, which engages behind the blind B having the hasp-piece.

I am aware that numerous changes may be made in the construction of my blind-fastener

by those who are skilled in the art without departing from the scope of my invention as expressed in the claims. I do not wish, therefore, to be limited to the construction I have herein shown and described; but

What I do claim, and desire to secure by Letters Patent of the United States, is—

As an article of manufacture, a blind-fastener comprising a hasp adapted to be secured to a blind, a socket-piece adapted to be secured to the sill, and a fastening-screw threaded into the socket-piece in position to engage and lock the hasp in the socket-piece.

In testimony whereof I have hereunto set my hand in the presence of two subscribing witnesses.

EDWARD FAVREAU.
